Term of patent 14 years

(Cl. D52—2)

FIG. 1

FIG. 2

FIG. 3

FIG. 1 is a front elevation of a gasoline pump service station unit embodying my new design.

FIG. 2 is a side elevation thereof.

FIG. 3 is a top plan view thereof.

The rear of the gasoline pump unit is substantially the same in appearance as the front, and the undisclosed side is substantially the same in appearance as the side shown.

The essential features of the design reside in the portions shown in full lines.

I claim:

The ornamental design for a gasoline pump service station unit, as shown and described.
